STOVE AND KETTLE COMBINATION

Peter Schlumbohm, 41 Murray St., New York, N.Y.

Filed July 20, 1959, Ser. No. 56,841

Term of patent 14 years

(Cl. D81—10)

The figure is a perspective view of a stove and kettle combination showing my new design.

The opposite side, which is not shown, offers the same appearance, except that there are no slots.

I claim:

The ornamental design for a stove and kettle combination, as shown and described.
